(57) **CLAIM**

The ornamental design for an arrow rest, as shown and described.

DESCRIPTION

FIG. 1 is a perspective view of the first embodiment of an arrow rest, showing my new design;

FIG. 2 is a top view thereof;

FIG. 3 is a bottom view thereof;

FIG. 4 is a left side view thereof;

FIG. 5 is a right side view thereof;

FIG. 6 is a front view thereof;

FIG. 7 is a rear view thereof;

FIG. 8 is a perspective view of the arrow rest of FIG. 1 shown with an unclaimed mounting bracket;

FIG. 9 is a perspective view of the second embodiment of an arrow rest, showing my new design;

FIG. 10 is a top view thereof;

FIG. 11 is a bottom view thereof;

FIG. 12 is a left side view thereof;

FIG. 13 is a right side view thereof;

FIG. 14 is a front view thereof; and,

FIG. 15 is a rear view thereof.

(Continued)

The evenly broken lines in the drawings form no part of the claimed design.
